UNITED STATES PATENT OFFICE.

ROBERT A. BROOKS, OF CHICAGO, ILLINOIS, ASSIGNOR TO CHICAGO SYPHO-METER MFG. CO., OF CHICAGO, ILLINOIS, A CORPORATION OF DELAWARE.

SIPHONIC FLUSHING DEVICE.

Application filed April 1, 1926. Serial No. 99,168.

My invention relates to a flushing device of the siphonic type, suitable for use in a water closet, whether it be used singly, or in a battery of such closets. The object of 5 my invention is to provide a simple and efficient device of improved construction, which by reason of certain novel and original features of construction and arrangement of the parts shall operate with certainty and precision, and be little liable to derangement because of sediment or foreign particles carried by the water with which it is operated, or from other causes. To this 10 end I have devised and invented the flushing devices illustrated in the accompanying drawings and hereinafter described in detail, my invention residing in the novel construction of the associated parts and members, functioning as described, as more 15 particularly pointed out in the appended claims; it being understood, however, that the particular construction described is susceptible of variation and modification and that I desire the claims to be construed 20 to cover all combinations of elements corresponding in purpose and function to those described and not departing substantially from the substance and spirit of my invention. 25

In the drawings, Figure 1 is a side view, on a small scale, of a master tank and two of my improved flushing devices, which may be taken to be devices installed in adjoining closets of a battery of closets supplied by a 30 single supply line controlled by the master tank; Fig. 2 is a central vertical section of a single device in the plane indicated by the dotted section line 2—2 of Fig. 1 and looking in the direction of the arrows; Fig. 3 is a top plan view of the same; Fig. 4 is a 35 central vertical section of the same in a plane at right angles to the plane of Fig. 2 and looking from left to right as the parts are shown in such figure; Fig. 5 is a horizontal section on planes indicated by the section line 5—5 of Fig. 4; Fig. 6 is a view of valve stem and valve, and a check valve carried thereby, detached, and partly in section; Fig. 7 is a detail of a regulating screw shown in 40 vertical section on the plane indicated by the dotted line 7—7 on Fig. 3; Fig. 8 is a perspective of a portion of the lower end of an adjustable sleeve on the lower end of an air-inlet tube forming part of the device for

timing the length of the flushing action of 55 the device, and Fig. 9 is a horizontal section of the same portion of the device in the plane indicated by the dotted line 9—9 of Fig. 4.

Like reference characters indicate like 60 parts in all the figures of the drawing.

It will be understood that the master tank 1 is connected with a service pipe 2 and is equipped with inlet valve mechanism 2^a, (shown in dotted lines) arranged to automatically control the admission of water and maintain it a given level therein, and that the supply pipe 3 is in open communication with the master tank and is arranged to supply the flushing devices, whether one or 70 more; the tank, supply pipe and flushing devices being arranged at a suitable height, say five or six feet,—to produce an efficient siphonic flushing action.

The supply pipe 3 may conveniently consist of sections united by fittings 4 which through a suitable intermediate member 5 and union 6 is arranged to support the inlet neck 7 of the flushing device. An inwardly-opening check valve 8 mounted to swing on 75 a segmental supporting pin 9 carried by a ring 10 secured to the neck 7 of the device permits water to flow freely into the device from the supply pipe, but prevents flow in the opposite direction.

The body 11 of the device is interiorly chambered to form a coned valve seat 11^a below the neck 7 and the lower end is exteriorly threaded for connection with the flushing pipe 12. In the present instance the portion of the casing of the device above the body 11 consists of a cylindrical shell 13 which at the top is closed by a flanged collar 14 and a cap 15 secured thereto, the latter being formed with a forked bracket 16 providing a pivotal support for the operating lever 17 by means of which the device is operated. An adjustable leak opening 90 through the cap 15 is provided by a slotted regulating screw 15^a which may be adjusted to vary the area of the slot opening exposed.

In the chamber within the body 11 and shell 13 of the casing is arranged an overflow pipe 18 which is equipped at its lower end with a valve member 19 arranged to cooperate with the valve seat 11^a before mentioned. Near its upper end this pipe 18 is orificed to receive a transversely arranged

85

90

95

100

105

guide pin 20 which is engaged by an orificed block 21 secured to the lower end of a lifting rod 22 which is slidably mounted in the cap 15 and is equipped at its top end with a flanged nut 23 arranged to be engaged by the forked end of the operating lever 17 before mentioned.

It is obvious that when the pipe 18 and valve 19 carried thereby are lifted by operation of the operating lever, water will flow by gravity through the flushing pipe 12, and that when the lever is released and the valve rescats the weight of the water column in the flushing pipe and overflow pipe (which then together form one leg of a siphon) will initiate a siphonic flow of water upwardly from the inlet of the device over the top of the overflow pipe, and this flow will continue until the siphon is relieved. This is accomplished through the regulating means next to be described.

The body 11 of the device is formed with a threaded boss 24 arranged to receive an elbow 25 within the horizontal bore of which a ball check valve 26 is arranged to seat against a hollow plug 27 seated within the end of the elbow. Adjacent the angle of the elbow, the elbow is formed with a stop 28 limiting its movement. To the vertical portion of the elbow is secured the base 29 of a casing enclosing a regulating chamber, this casing including the base 29, a cylindrical shell 30 and a cap 31 formed with an air opening 31a. The cap 31 is provided with a central boss through which passes an air inlet tube 32 secured to an elbow 33 having a horizontal member which makes a snug slip joint connection with a section of the air inlet tube extending downwardly through the cap 15 of the device into the overflow pipe to a point a short distance below the top of such pipe. The lower end of the air inlet tube 32 within the regulating chamber is slotted and equipped with a split regulating sleeve 34 arranged to expose more or less of the slot above the lower end of such tube. To this end the lower end of the tube is formed with a short longitudinal corrugation 32a which coacts with the edges of the sleeve along its split opening in such manner as to yieldingly retain it in any position of longitudinal adjustment on the tube.

In axial alignment with the air inlet tube 32, the elbow 33 is formed with a valve seat arranged to cooperate with an air inlet valve 35 carried by the upper end of a valve rod 36 extending axially through the inlet tube and adapted to be lifted by a cup 37 arranged within the regulating chamber, in a manner later to be described. The lower end of the valve rod is headed and slidably supports a check valve 38 which cooperates with the lower end of the air inlet tube under certain conditions arising during the operation of the valve, the adjusting sleeve 34 pro-

viding for a regulated and restricted flow of water past such valve 34 to govern the timing of the flushing operation.

When the operating lever is lifted and released and a siphonic flushing flow initiated as hereinbefore described, the reduction in pressure opposite the ball check valve 26 causes such valve to seat against the plug 37, and the reduction of pressure also extends through the air inlet tube 32 and causes the check valve 38 to be immediately lifted to seat against the lower end of such tube, and then draws water from the regulating chamber on the inside of the cup 37 at a rate determined by the adjustment of the sleeve 34. When the water in the regulating chamber sinks below the top of the cup, water is of course drawn from the cup only, and when it has been drawn from the cup to a level where its buoyancy exceeds its weight it begins to float and rise in the chamber, the level of the water between the sides of the cup receding as water is drawn from within the cup and its lifting effect increases. When the water in the cup is drawn off to the level of the opening through the sleeve 34 of the air inlet tube, air is drawn through the tube and immediately relieves the siphon in the flushing pipe at the end of the air inlet tube, the water in the column below the end of the air inlet tube falling through the flushing pipe and terminating the main flushing flow, and the portion of the tube above such level continuing to draw a much reduced flow of water siphonically over the top of the overflow pipe to produce an after flush.

The breaking of the flushing flow of the siphon practically restores the gravity pressure opposite the ball check valve 26 and permits a somewhat restricted flow past such valve into the regulating chamber. At the time the siphon is broken the water in the cup has been drawn down to a level at which air is admitted through the inlet tube to break the main flush of the siphon and the cup has floated to a level adjacent or contacting the lower end of the valve rod 36. The inflow of water past the ball check into the regulating chamber then raises the cup and also the valve rod and the valve 35 to uppermost position, thus providing the air inlet tube with an air inlet past such valve in addition to the one at the slotted lower end of the tube, or in place of such last mentioned opening in case the lifting of the cup causes submergence of the lower end of the tube. This final upward movement occurs quickly, and the further restricted flow of water into the regulating chamber causes the water to gradually overflow into the cup until its buoyancy is overcome, when it at once sinks to normal lower position, restoring the air inlet valve to closed position,

ready for a further flushing operation as soon as the normal water level in the regulating chamber is reached.

In the meantime the after flush due to the short column of water remaining at the top of the siphon chamber (above the end of the air inlet tube) continues until enough air is drawn in through the leak opening in the regulating screw 15^a, to entirely break the siphon, thus stopping all flow of water through the flushing pipe. It will be understood that the main flush through the siphon is so active that it entrains all the air which can pass through this leak port, which therefore does not affect the flushing operation. The amount of after flow can be regulated by adjustment of the screw which controls the size of the leak opening.

The operation of any one device of a battery of closets obviously causes a reduction of pressure which extends to the adjacent portion of the main supply line and, especially in the event of simultaneous flushing of several adjacent closets, this might result in exhausting the water from the short legs of the siphons of the unused adjacent devices and drawing air upwardly through the flushing pipes connected thereto, except for the provision of the check valves 8, which serve to prevent back flow and maintain a sufficient body of water in such devices to insure the initiation of a siphonic flush in any particular closet upon actuation of the operating lever.

I claim:

1. In combination with a supply tank provided with means for maintaining a constant level of water therein, a flushing device including a casing formed with a vertically disposed closed chamber communicating laterally with said supply tank and arranged to contain water at the level of such tank, a flushing pipe communicating with said chamber below its supply connection, an overflow pipe in said chamber formed at its lower end with a valve governing communication between the annular space around said pipe and said flushing pipe, and means for lifting said overflow pipe to initiate a flush of water through said flushing pipe, said overflow pipe and flushing pipe together acting as a siphon to continue the flush upon the lowering of the overflow pipe.

2. In combination with a supply tank provided with means for maintaining a constant level of water therein, a flushing device including a casing formed with a vertically disposed closed chamber, a supply connection in communication with said master tank and opening laterally into said chamber, an inwardly opening check valve governing communication through said supply connection, a flushing pipe com-

municating with said chamber below its supply connection, an overflow pipe in said chamber formed at its lower end with a valve governing communication between the annular space around said pipe and said flushing pipe, and means for lifting said overflow pipe to initiate a flush of water through said flushing pipe, said overflow pipe and flushing pipe together acting as a siphon to continue the flush upon the lowering of the overflow pipe.

3. In combination with a master supply tank provided with means for maintaining a constant level of water therein and a line of supply piping in open communication with said tank, a plurality of flushing devices each including a casing formed with a vertically disposed chamber and supply connection communicating with said supply piping and opening laterally into said chamber, an inwardly opening check valve governing communication through said supply connection, a flushing pipe communicating with said chamber below its supply connection, an overflow pipe in said chamber formed at its lower end with a valve governing communication between the annular space around said pipe and said flushing pipe, and means for lifting said overflow pipe to initiate a flush of water through said flushing pipe, said overflow pipe and flushing pipe together acting as a siphon to continue the flush upon the lowering of the overflow pipe.

4. A flushing device according to claim 1 in which said casing and said overflow pipe are concentrically arranged cylindrical members and said overflow pipe is equipped with laterally extending guide members adjacent its top.

5. A flushing device according to claim 1 in which said casing and said overflow pipe are concentrically arranged cylindrical members and said casing is formed with a coned valve seat at its bottom and the lower end of said overflow pipe is equipped with a radially extending annular valve.

6. In combination with a supply tank provided with means for maintaining a constant level of water therein, a flushing device including a casing formed with a vertically disposed closed chamber communicating laterally with said supply tank and arranged to contain water at the level of such tank, a flushing pipe communicating with said chamber below its supply connection, an overflow pipe in said chamber formed at its lower end with a valve governing communication between the annular space around said pipe and said flushing pipe, means for lifting said overflow pipe to initiate a flush of water through said flushing pipe, said overflow pipe and flushing pipe together acting as a siphon to continue the flush upon the lowering of the

overflow pipe, and means for regulating the length of main siphonic flush and producing a diminished after flow including casing members formed with a regulating chamber 5 having check-valve-governed communication with said first mentioned chamber, and an air inlet tube having depending branches extending into said overflow tube and into the lower end of said regulating chamber, 10 said air inlet tube having restricted communication with said regulating chamber.

7. In combination with a supply tank provided with means for maintaining a constant level of water therein, a flushing device including a casing formed with a vertically disposed closed chamber provided with a leak port at its top, said chamber communicating laterally near its lower end with said supply tank and being arranged 15 to contain water at the level of such tank, a flushing pipe communicating with said chamber below its supply connection, an overflow pipe in said chamber formed at its lower end with a valve governing communication 20 between the annular space around said pipe and said flushing pipe, means for lifting said overflow pipe to initiate a main flush of water through said flushing pipe, said overflow pipe and flushing pipe together acting as a siphon to continue said flush upon the lowering of the overflow pipe, and means for regulating the length of said main flush and producing a diminished after 25 flow including a regulating chamber having check-valve-governed communication adjacent its lower end with said first mentioned chamber, and an air inlet tube having depending branches extending one into said overflow tube and the other into the lower 30 end of said regulating chamber, said air inlet tube having restricted communication with said regulating chamber.

8. In a siphonic flushing device including a closed casing formed with flow passages 45 constituting the short and long legs of the siphon, means for initiating a main siphonic flushing flow, and means for regulating the length of said flushing flow and producing a diminished siphonic after flow including 50 casing members formed with a regulating chamber, said regulating chamber having check-valve-governed communication adjacent its lower end with the shorter leg of the siphon, an air inlet tube having depending branches extending one into the long leg of the siphon and the other into the lower 55 end of said regulating chamber, said air inlet tube having restricted communication with said regulating chamber and being arranged to interrupt the main siphonic flushing flow when the water level is reduced in the regulating chamber, and means for admitting air to the crown of the siphon to 60 interrupt the after flow.

9. In a siphonic flushing device including

a closed casing formed with flow passages constituting the short and long legs of the siphon, means for initiating a main siphonic flushing flow, and means for regulating the length of said flushing flow and producing a diminished siphonic after flow including 70 casing members formed with a regulating chamber, said regulating chamber having check-valve-governed communication adjacent the lower end with the shorter leg of the siphon, an air inlet tube having depending branches extending one into the long leg of the siphon and the other into the lower end of said regulating chamber, said air inlet tube having restricted communication with said regulating chamber and being arranged to interrupt the main siphonic flushing flow when the water level is reduced in the regulating chamber, float-controlled 75 means for admitting air to said air inlet tube intermediate its ends, and means for admitting air to the crown of the siphon to interrupt the afterflow.

10. In a siphonic flushing device including a closed casing formed with flow passages constituting the short and long legs of the siphon, means for initiating a main siphonic flushing flow, and means for regulating the length of said flushing flow and producing a diminished siphonic after flow 80 including casing members formed with a regulating chamber, said regulating chamber having check-valve-governed communication adjacent its lower end with the shorter leg of the siphon, a cup arranged within said regulating chamber, an air inlet tube having depending branches extending one into the long leg of the siphon and the other into said cup, said air inlet tube having restricted communication with the space inside said cup, and a valve rod extending through the branch of said air inlet tube which extends into said cup equipped with a valve arranged to open communication 85 with the atmosphere at its upper end, said valve stem being arranged to be actuated by flotation of said cup.

11. In a siphonic flushing device including a closed casing formed with flow passages constituting the short and long legs of the siphon, means for initiating a main siphonic flushing flow, and means for regulating the length of said flushing flow and producing a diminished siphonic after 90 flow including casing members formed with a regulating chamber, said regulating chamber having check-valve-governed communication adjacent its lower end with the shorter leg of the siphon, a cup arranged within said regulating chamber, an air inlet tube having depending branches extending one into the long leg of the siphon and the other having a slotted lower end extending into said cup, a headed valve rod extending through said 95

last mentioned branch equipped with a valve arranged to open communication with the atmosphere at its upper end, said valve stem being arranged to be actuated by flotation of said cup, and a check valve on the lower end of said valve rod adapted to cooperate with the lower slotted end of said air inlet tube.

12. In a siphonic flushing device including a closed casing formed with flow passages constituting the short and long legs of the siphon, means for initiating a main siphonic flushing flow, and means for regulating the length of said flushing flow and producing a diminished siphonic after flow including casing members formed with a regulating chamber, said regulating chamber having check-valve-governed communication adjacent its lower end with the shorter leg of the siphon, a cup arranged within said regulating chamber, an air inlet tube having depending branches extending one into the long leg of the siphon and the other having a slotted lower end extending into said cup, a headed valve rod extending through said last mentioned branch equipped with a valve arranged to open communication with the atmosphere at its upper end, said valve stem being arranged to be actuated by flotation of said cup, and a check valve on the lower end of said valve rod adapted to cooperate with the lower slotted end of said

air inlet tube, said slotted end being equipped with an adjusting sleeve arranged to vary the area of the slot opening exposed.

13. In a siphonic flushing device including a closed casing formed with flow passages constituting the short and long legs of the siphon, said casing being provided with a leak opening at the crown of the siphon, means for initiating a main siphonic flushing flow, and means for regulating the length of said flushing flow and producing a diminished siphonic after flow including casing members formed with a regulating chamber, said regulating chamber having check-valve-governed communication adjacent its lower end with the shorter leg of the siphon, a cup arranged within said regulating chamber, an air inlet tube having depending branches extending one into the long leg of the siphon and the other into said cup, said air inlet tube having restricted communication with the space inside said cup, and a valve rod extending through the branch of said air inlet tube which extends into said cup equipped with a valve arranged to open communication with the atmosphere at its upper end, said valve stem being arranged to be actuated by flotation of said cup.

In testimony whereof, I have subscribed my name.

ROBERT A. BROOKS.
